Application October 15, 1932, Serial No. 637,867

19 Claims. (Cl. 120—18)

This invention pertains to mechanical pencils, and is particularly applicable in pencils of the magazine type wherein lead sticks are fed successively from a magazine to the writing point in accordance with requirements for use.

A general object of the invention is the provision of an improved construction for such pencils which will be economical to manufacture, easily assembled and disassembled, and 10 which will be certain and positive in operation.

A particular object of the invention is the provision of such a construction which will be very sturdy even though the parts may be quite small, and which will be effective to minimize 15 destructive wear of the operating parts.

Another object is the provision of such a construction which is particularly adapted for embodiment in quite slender pencils.

Another particular object is the provision of 20 a magazine pencil adapted to feed a succession of lead sticks automatically from the magazine to the writing point and which is operable to effect both the propulsion and retraction of the lead to and from the writing point as desired.

Another particular object is the provision of 25 a construction adapted to effect the close following-on of one lead stick after another and preclude retraction of the lead sticks into the magazine after they have passed therefrom on their 30 way to the writing tip.

Yet another object is the provision of a construction which will firmly hold the lead in writing position, yet is operable to effect any desired longitudinal adjustment of the lead relative to 35 the writing tip.

Yet another special object is the provision of a construction serving to safeguard the lead-handling parts against injury from lead sticks of excessive diameter.

Other and further objects of the invention 40 will be pointed out or indicated hereinafter, or will be apparent upon an understanding of the invention or its employment in use.

For the purpose of aiding in an explanation 45 of the invention, I show in the drawings forming a part of this specification, and hereinafter describe, certain preferred embodiments of the same, but it is to be understood that these are here presented merely for purpose of illustration, and hence are not to be construed in any fashion calculated to limit the appended claims short of the true and most comprehensive scope of the invention in the art.

In said drawings, 50 Fig. 1 is a longitudinal section through the

lower portion of a mechanical pencil containing one embodiment of the invention;

Fig. 2 is a broken longitudinal section through the upper portion of such a pencil;

Fig. 3 is a cross section on approximately line 60 3—3 of Fig. 2, but with the eraser and eraser ferrule removed;

Fig. 4 is a cross section on approximately line 65 4—4 of Fig. 2, but with the actuator sleeve removed;

Fig. 5 is a cross section on approximately line 5—5 of Fig. 2;

Fig. 6 is a cross section on approximately line 6—6 of Fig. 1;

Fig. 7 is a cross section on approximately 70 line 7—7 of Fig. 1;

Fig. 8 is a full length longitudinal section of a pencil containing the structural features illustrated in the foregoing figures and with lead sticks therein as in normal operating condition; 75

Fig. 9 is a perspective illustration of the traveller which forms part of the lead-propelling mechanism;

Fig. 10 is a perspective illustration of the pawl lifter; 80

Fig. 11 is a longitudinal section corresponding to that illustrated in Fig. 1, but of a slightly modified construction; and

Fig. 12 is an end elevational view of the tip shown in Fig. 11, on a somewhat larger scale. 85

Described generally, the present invention, in one particular, comprises a mechanical pencil having in its upper portion a magazine adapted to contain a plurality of lead sticks side by side, said magazine being provided with a constricted passage through its bottom adapted to permit the passage of lead sticks singly and in succession from the magazine into a lead guide channel which conducts the lead sticks to the lower end of the pencil. A lead-propelling device is movable longitudinally in the pencil and is adapted to engage a lead stick in the guide channel and propel it toward the tip, a succeeding lead stick meanwhile following on in the lead channel. When the lead-propelling device reaches its limit of downward movement, its lead-engaging member is lifted or cast off to a position where it is entirely clear of the lead sticks in the guide channel, wherefore the lead-propelling device may be fully retracted 90 to its upper limit position entirely out of engagement with any of the lead sticks in the lead guide channel, and then upon again starting its downward movement, will be effective to engage a lead stick in the channel and feed 100

105

110

it on toward the writing tip to any desired extent. The lead may be thus propelled to an extent equaling the full length of a lead stick, without retraction of the lead-propelling device 5 between the successive lead-propelling operations.

For writing, the lead stick in writing position is definitely held by the lead-propelling mechanism against return movement under writing 10 pressure. Provision is made, however, for a retractive movement of the lead at the writing point when desired. This is accomplished by the provision of a lead-clutching member adapted to clasp the lead stick frictionally as the lead 15 stick is moved toward the writing point. This clutch is adapted to move with the lead stick for a limited distance in its propelling movement under pressure from the lead-propelling device; and upon the backing up of the lead-propelling 20 device, this clutch is adapted to return upwardly a corresponding distance and carry with it the lead stick at the writing point, thus giving the lead stick a retractive movement, the extent of which, within the range of movement of the 25 clutch, is determined by the distance to which the lead-propelling device is backed up.

The foregoing serving as a rather general description of certain features of the invention, the nature of the same and of other and more 30 detailed features will be most quickly understood by a consideration of certain illustrative embodiments, which will now be described.

Referring first to the construction illustrated in Figs. 1 to 10 inclusive of the drawings, it will 35 be understood that the pencil has a hollow barrel, here made up of the straight tubular portion 15 and tapered portion 16 which are connected at 17 by screw thread engagement. The tapered portion 16 has a reduced bore in its 40 lower portion, in which is seated a liner sleeve 18, for the most part cylindrical, but flattened at 18^a as illustrated in Fig. 7. At the upper end of the liner sleeve 18, the bore of the tapered portion is enlarged to provide a shoulder 18^b, above 45 which the bore takes a flaring form for a short distance, and thence continues in its cylindrical form to the upper end of the tapered portion.

A lead guide tube 19 extends through the lower portion of the bore of the barrel, and has a 50 squared or flattened portion which fits in the flattened portion 18^a of the liner sleeve, to hold the lead guide tube against rotation with respect to the barrel. At its lower end the lead guide tube is threaded for screw connection with the 55 tip 20, which has a circumferential shoulder that abuts the lower end of the barrel and sleeve 18 at 20^a. Adjacent the shoulder 18^b the lead guide tube is formed with a peripheral shoulder 19^a, and a bearing collar 21 is rotatably fitted 60 on the lead guide tube at this point, said collar having at its lower end a short inwardly extending flange which on its upper side abuts the shoulder 19^a and on its lower side abuts the end of the liner sleeve 18.

The lead guide tube has a longitudinal bore 65 which aligns with the bore of the tip, and at one side the lead guide tube is flattened off for the greater portion of its length, as illustrated at 19^b in Fig. 6, and is slotted through the flattened portion to provide a longitudinal slot 19^c. The upper end of the lead guide tube is counterbored and has fitted therein a short tube section 22, the bore of which aligns with the bore of the lead guide tube, and which tube section has 70 affixed to its upper end a disk 24 which, by 75

virtue of the connection, is held stationary with the lead guide tube.

An actuator sleeve is rotatably mounted in the barrel, the upper portion 25 of said sleeve being cylindrical and extending above the upper end 80 of the barrel. This upper portion of the actuator sleeve constitutes the wall of the lead stick magazine, and fits closely but rotatably about the periphery of the disk 24. The disk 24 constitutes the bottom of the lead stick magazine, and is provided with a central aperture 24^a of such size as to accommodate the passage of lead sticks singly from the magazine into the lead guide tube. The upper surface of the disk 24 is dished or concave, so that it slopes 85 toward the aperture 24^a, and is provided with a shallow groove 24^b extending outwardly from said aperture.

The lower portion 25^a of the actuator sleeve is formed with a coarse helical thread or threads 90 of rather steep pitch, and the lower end part of said sleeve is tapered so as to fit in the flaring portion of the barrel bore. The bearing collar 26 is fitted in the lower end of the actuator sleeve and held in place therein by portions of 95 the sleeve which are punched into peripheral depressions in the collar. The collar 26 and the lower end of the actuator sleeve abut the shoulder 18^b, the collar 26 rotatably fitting the collar 21, and at its upper end abutting an outwardly 100 extending flange 21^a of the collar 21. By virtue of these connections the actuator sleeve is held against withdrawal upwardly from the barrel while the lead guide tube is connected to the tip, yet the actuator sleeve may rotate freely in the 105 barrel about the lead guide tube. To impose a desirable amount of drag or friction on the actuator sleeve, whereby to prevent its rotating too freely, a bushing 27 is disposed in the upper 110 end of the barrel, said bushing being slotted to 115 form spring leaves 27^a which have a set such as to give them an inward spring tendency, as illustrated in Fig. 4. The resilient pressure of these leaves against the periphery of the actuator sleeve opposes a yieldable resistance to its 120 rotation, for the purpose hereinafter explained. Within the lead magazine is arranged a flight 125 28 which extends inwardly for a short distance from the magazine wall, the purpose of the same being to move the lead sticks in the magazine 130 about on the magazine bottom incident to rotation of the actuator sleeve, whereby to contribute to their entry into the aperture 24^a.

Somewhat below the upper end of the actuator sleeve a gauge 29 is fixed therein, same 130 serving to close the upper end of the magazine, excepting for a gauge aperture 29^a, the width of which is such as just to permit passage therethrough of lead sticks having a predetermined 135 diameter but the length of the gauge opening being such as to permit passage of a plurality of such lead sticks simultaneously. An eraser 30 is movably mounted in the upper end of the actuator sleeve by means of a split ferrule 31 which clamps the eraser, said ferrule being provided adjacent its upper end with an outwardly 140 extending portion 31^a adapted to contact the upper end of the actuator sleeve. A cap 32 fits on the projecting portion of the actuator sleeve and houses the eraser. This cap is provided with longitudinal internal grooves 32^a adapted to receive outwardly projecting portions 34 of the actuator sleeve, whereby to key the cap to the actuator sleeve so that the latter will 145 be rotated by rotational manipulation of the cap. 150

The cap is also provided with inwardly projecting elements 32^b which frictionally engage the peripheral surface of the actuator sleeve to restrain the cap in place, said cap being removable upwardly from the sleeve upon application of sufficient force.

Slidably longitudinally on the lead guide tube is a traveler 35, shown in full detail in Fig. 9. It is formed with an axially extending cavity 35^a shaped to fit the peripheral contour of the lead guide tube, whereby the traveler is retained against rotation with respect to said tube. On the side corresponding to the flattened side of the lead guide tube, the traveler is milled out to form longitudinal ribs 35^b which are separated by a slot that extends into the cavity 35^a. The upper edges of said ribs and the peripheral portion of the traveler are provided with helical threads 35^c adapted to mesh with the thread 20 of the actuator sleeve. A lead-engaging member 36, in the nature of a pawl, is pivotally mounted in the slot between the ribs 35^b and on the pintle 37^a which extends through aligned apertures in the pawl and ribs 35^b. This pintle is an end portion of a wire spring 37 which encompasses the ribs 35^b and has its other end extending across and engaging the projecting end of the pawl. The spring member is held in position by a lug 38 on the traveler which is bent over to engage the spring member and hold it down, as shown in Fig. 6.

The nose of the pawl 36 is of such size that it may enter through the slot 19^c and into the bore of the lead guide tube, and the tendency 25 of the spring member 37 is such as to press the pawl to that position. Adjacent its nose the pawl is provided with a laterally projecting latching wedge 36^a adapted to overlap and ride upon the flattened surface of the lead guide 40 tube along the slot 19^c and limit the extent to which the nose of the pawl may enter the bore of the lead guide tube.

Slidably mounted on the lead guide tube is a pawl lifter or throw-off member 39, illustrated 45 in detail in Fig. 10. This is in the nature of a collar or bushing having an axial cavity 39^a shaped to fit the contour of the lead guide tube, whereby the throw-off member is held against rotation with respect to said tube. The throw-off member is slotted longitudinally at 39^b for a portion of its length, said slot being open at the end facing the traveler and being of width such as to accommodate the nose portion of the pawl but not the latching wedge 36^a. The 55 throw-off member is milled transversely of the slot to provide the pawl-lifting and latching lugs 39^c, which have faces extending obliquely to the axis of the throw-off member.

In operation of the lead-handling parts so far described, rotation of the actuator sleeve in one direction will cause the traveler to move downwardly in the barrel, the nose of the lead-engaging member 36 traveling in the slot 19^c and extending into the bore of the lead guide tube. When the traveler is about to attain the limit of its downward movement, the wedge 36^a of the pawl will engage the upper sloping faces of the pawl-lifting lugs 39^c, and as downward movement of the traveler continues, the lower end of the pawl will be wedged outwardly, the pawl swinging on its pivot, until the nose of the pawl is lifted out of the bore of the lead guide tube. When the wedge 36^a passes over the high point of the lugs 39^c, it will engage behind the lower latching surfaces of said lugs, thereby re-

taining the nose of the pawl in the lifted position, and latching the throw-off member 39 to the traveler. This operation takes place when the throw-off member is in its lower limit position as shown in Fig. 1, where it abuts the upper end of the collar 21. The dotted line position of the traveler and pawl shown in Fig. 1 is that occupied by these parts when the traveler has reached its lower limit of travel and the throw-off member is latched to the traveler. Thereupon, rotation of the actuator sleeve in the opposite direction, will slide the traveler upwardly on the lead guide tube, the traveler carrying the throw-off member with it because of the latching engagement of the latching wedge 36^a with the lugs 39^c. The traveler, with the throw-off member thus latched to it, is thus moved to its upper limit position, which is that illustrated in Fig. 2. Just before the traveler attains this position, the throw-off member 39 is stopped by coming up against a stop member 40 which is formed on the lead guide tube, the traveler having been permitted to pass such stop by virtue of the groove 35^d through which the stop 40 may pass. The continuing upward movement of the traveler after the throw-off member is thus stopped wedges the projecting end of the pawl outwardly, thus freeing the throw-off member from the traveler and permitting it to slide freely downwardly on the lead 105 guide tube. The pawl is held in its lifted position by virtue of the engagement of its nose on the lower portion of the unslotted tube section 22.

It will thus be observed that during the entire 110 upward or retracting movement of the traveler, the lead-engaging member is held entirely clear of the bore of the lead guide tube, this to prevent its engaging lead sticks which may be in that tube and to preclude its dragging such lead 115 sticks upwardly with it.

For the purpose of accomplishing a repelling or retractive adjustment of the lead at the writing point, under control of the lead-feeding mechanism, I provide a slidable clutch or 120 lead-gripping member in the form of a sleeve 41 in position to engage a lead stick below the lead-engaging member 36. In the arrangement illustrated in Fig. 1 this sleeve is located in the bore of the tip 20, which is enlarged to accommodate a coiled spring 42 which encompasses the sleeve 41 and bears at its upper end against a flange 41^a at the upper end of said sleeve, and at its lower end against a shoulder 20^b in the tip. The bore of the sleeve 41 is in alignment 125 with the bore of the lead guide tube 19, so that a lead stick propelled downwardly from the latter will pass through said sleeve. The sleeve 41 has lead-gripping members 41^b adapted to grip firmly a lead stick in the tip bore, yet permit downward movement of such lead stick upon application of sufficient propelling pressure thereto. The bore of the tip below the sleeve 41 is of such size as to permit the latter a substantial extent of movement downwardly therein, the 130 limit of such movement being fixed by a stop 44 in position to engage the sleeve 41. The bore of the tip below the shoulder 44 is of such size as to permit a lead stick to slide freely therein.

As a lead stick is propelled through the sleeve 145 41 by the lead-propelling mechanism, it encounters yieldable resistance from the lead-gripping members 41^b sufficient to overcome the power of spring 42, so that with the continuation of the lead-propelling movement, the sleeve 150

41 is slid downwardly and the spring 42 compressed. The downward movement of the sleeve 41 is arrested by the stop 44, whereupon further propelling movement of the lead stick will slide it downwardly through sleeve 41 and project its end portion beyond the terminus of the tip. The lead stick is retained in this position by the lead-engaging member 36 in abutment with the upper end of the lead stick which is in the tip or a following lead stick which is in end abutment with it, the spring 42 being held compressed on account of the frictional engagement of the lead-gripping members 41^b with the lowermost lead stick. Consequently, if the traveler 35 is then retracted by operation of the actuator, spring 42 will be allowed to expand and slide the sleeve 41 upwardly, thereby retracting the lead stick which is gripped by the members 41^b. Thus if the lead stick has been projected too far from the tip, it may be retracted to the extent that the sleeve 41 is movable. Upward movement of the sleeve 41 is limited by engagement of its upper end with the lower end of the lead guide tube 19.

25 It will be observed that retention of the lead stick against repulsion from writing position is dependent on lead-engaging member 36. In order to obtain rapid longitudinal adjustment of the traveler 35 and lead-engaging member 36 by rotation of the actuator, it is desirable that the thread of the latter be of rather high pitch, in order to be quick acting. In order to prevent the traveler's being backed up by upward pressure on the lead stick, as when the pencil is employed in writing, the resistance elements 27^a are provided for the purpose of imposing the requisite resistance to rotation of the actuator to prevent its being rotated by the camming action of the traveler threads on the quick thread of the actuator under the force which may be exerted on the lead-engaging member 36 through the lead stick or lead sticks which are below it.

It is to be observed also that the construction is such as to hold the lead very firmly in writing position and to feed it very positively and accurately without subjecting the small operating parts to distorting strains. In this particular, it is to be noted that the lead-engaging member 36 is a rigid element and that its active lever arm is quite short and that it acts as a straight rigid toggle element between its pivot and the end of the lead stick upon which it acts. The reaction of the lead-propelling pressure upon the lead-engaging member 36 tends to swing its lower end inwardly, but this resultant force is assumed by the wedge 36^a and transmitted to the lead guide tube by virtue of the bearing of the wedge upon its flattened portion.

30 The construction is such that the device may be assembled very conveniently and accurately. In the assembly of the lead-engaging member on the traveler, the shank of the pawl is inserted in the slot between the ribs 35^b with the nose of the pawl depressed, the pintle of the spring member 37 is inserted through the aligned apertures of the pawl and ribs 35^b with the rear end of the spring member in elevated position, the spring member then swung down to the position shown in Fig. 9, and the lug 38 peened over to secure it in position. The pawl lifter 39 is then slipped onto the lead guide tube at its upper end, followed by the traveler 35, and the tube section 22 with its disk 24 are then fixed to the lead guide tube. The bearing collar 21 is slipped onto

the lead guide tube at its lower end, and the lead guide tube inserted into the actuator through the upper end thereof, the traveler being at its upper limit position so that the lower end of the lead guide tube will protrude beyond the lower end of the actuator sleeve. The actuator sleeve is then rotated about the lead guide tube while the latter is held stationary, this serving to engage the thread of the actuator sleeve with the thread of the traveler and propel the latter to its lower limit position. The flight 28 is then inserted through the upper end of the actuator and moved to proper position in the magazine, being there retained by the expansive pressure of its resilient band 28^a. The gauge member 29 is then inserted to proper position against its supporting stops 33, where it is held in place by the constraining pressure of the encompassing portion of the actuator sleeve. The friction bushing 27 having been inserted to proper position in the upper end of the barrel, the actuator sleeve, with the other parts thus assembled therein, is then inserted through the upper end of the barrel until the collars 21 and 26 contact the shoulder 18^b, the squared portion of the lead guide tube fitting in the squared portion 18^a of the liner sleeve 18. The tip 20, having had the spring 42 and sleeve 41 assembled therein, is then inserted through the lower end of the barrel and screwed onto the lower end of the lead guide tube until the shoulder 20^a is drawn up into tight abutment with the lower end of the barrel and liner sleeve 18. This secures all of the operating parts in the barrel. Suitable lead sticks may then be inserted into the magazine through the gauge aperture 29^a, and the eraser ferrule with the eraser therein then inserted in the upper end of the actuator sleeve, and finally the cap 32 placed in position. The device is thus completely assembled.

114 In operation of the pencil, the barrel being held with the point downward, manual rotation of the cap 32 will rotate the actuator sleeve, such movement causing a shifting of the lead sticks about on the stationary magazine bottom 24, the flight 28 contributing to such movement of the sticks to positions where some of them will drop successively through the aperture 24^a into the lead guide tube. Assuming that the traveler is in its lower limit position at the start of such rotation of the actuator sleeve, it will be drawn upwardly, the lead-engaging member 36 being latched on the throw-off member 39 and dragging the latter upwardly with the traveler. The first lead stick to enter the lead guide tube may slide downwardly therein until stopped by the lead-gripping members 41^b, another lead stick or other lead sticks following it in succession. Upon the traveler's reaching its upper limit of travel, the lead-engaging member 36 will be unlatched from the pawl lifter 19, freeing the latter and permitting it to slide down on the lead guide tube. Then upon rotation of the actuator sleeve in the lead-feeding direction, the traveler 35 will be propelled downwardly, the nose of the lead-engaging member 36 dropping through the slot 19^a when it rides off of the short tube section 22, and thus being in position to engage against the upper end of one of the lead sticks in the lead guide tube. Continued downward propulsion of the traveler 35 will force the lowermost lead stick between the lead-gripping members 41^b and slide the sleeve 41 downwardly against the pressure of spring 42 as above described, the end 150

of the lead stick being projected through the tip upon the sliding of the lead stick through the sleeve 41 after the latter has reached its lower limit position. With the parts in this relationship, the lowermost lead stick is held by the gripping action of the members 41^b against falling out, and it is held against return movement by the abutment of the lead-engaging member 36 against its upper end or against the end of a following lead stick. It will be observed that as the traveler is moved downwardly, another lead stick may follow it down the lead guide tube, the lower end of such lead stick contacting the upwardly presented surface of the nose of the lead-engaging member. As the traveler attains its lower limit position, the lead-engaging member will be lifted out of the lead tube bore by the wedging action of the lugs 39^c against its wedge 36^a, and will be held in this cast-off position throughout the return movement of the traveler, thus permitting a lead stick which has followed the traveler in its downward movement to remain in its advanced position in the lead guide tube, ready to be propelled on toward the tip by the ensuing lead-feeding movement of the traveler.

In the modified construction illustrated in Figs. 11 and 12, the construction and arrangement of parts is as above described, excepting that the arrangement for automatically retracting or repelling the lead is omitted and a tip of different character is employed. In Fig. 11 the various parts corresponding to those above described are designated by corresponding reference characters.

The tip 45 in this construction is adapted to clutch or grip the lead stick which is in writing position, the lower portion of the tip bore being somewhat smaller than the cross section of the contemplated lead stick, and the tip being split from its lower end for a short distance so as to render the end portion of the tip resiliently expansible to accommodate the lead stick when it is propelled into the reduced bore portion and to exert a resilient gripping action upon it. The particular form of tip here shown is specially adapted for use of lead sticks of squared cross section, the terminal portion of the tip bore being squared, as illustrated in Fig. 12, and the end portion of the tip being cleft diagonally of the bore, as indicated at 45^a. In order to position the lead stick rotatably incident to its movement to the squared bore, so that it may register properly therein, positioning members 45^b are extended for a short distance upwardly from the flattened sides of the bore into the superjacent cylindrical portion of the bore, said positioning members being formed integrally with the tip as inward protrusions from the cylindrical wall. They have diagonally sloping upper margins which terminate adjacent the corners of the squared bore. Consequently, if a lead stick, when it approaches the squared bore, is not in proper rotative position to register therein, a corner of the stick will engage the diagonal margin of the positioning member, and the lead stick will be cammed around to proper rotative position incident to its advancing movement. This particular form of tip is part of the subject matter of a co-pending application of Robert Back, Serial No. 630,261, filed August 24, 1932, and is here shown for the purpose of illustrating one of various alternative tip constructions which may be employed in the combination constituting the present invention.

It will be observed that in the propelling operation, the propelling pressure is delivered positively to the lead stick by virtue of the abutment of the lead-engaging member against its end, this, together with the fact that the lead-engaging member is rigid and unyielding under the propelling pressure, accomplishing a positive and certain advancement of the lead upon propelling movement of the traveler. It will further be observed that the spring member which holds the lead-engaging member in lead-engaging position is entirely free from the lead-propelling pressure. It is also to be observed that by virtue of the construction, this spring member may be made comparatively long, so that its elastic flection is well distributed, thus tending to preclude crystallization or fatigue at any particular point in it and thus contributing to its serviceable endurance. It is also to be observed that its extent of flection is quite short.

Although not necessarily the case, it is preferable to limit the length of the magazine, that is, the distance between the magazine bottom and the gauge member 29, to a length less than the distance of travel of the lead-engaging member. This serves as a limitation upon the length of lead sticks which may be inserted in the pencil and insures that they will not be so long as to prevent the lead-engaging member's making proper engagement with the upper end of some one of the lead sticks in the lead guide tube.

Having thus described the nature and character of my invention, and various examples of its embodiment, I claim as my invention:

1. In a mechanical pencil having a barrel and a lead stick magazine spaced from the lower end of the barrel, the combination of a lead guide tube for conducting a lead stick from the magazine toward the lower end of the barrel, a lead-engaging member adapted to engage a lead stick in said tube, means for moving the lead-engaging member in both directions longitudinally of the tube, and throw-off means engageable with the lead-engaging member at the end of its downward movement and effective to hold the lead-engaging member out of engagement with lead sticks in said tube during upward movement of said member.

2. In a mechanical pencil having a lead outlet at its lower end and a lead stick magazine spaced upwardly therefrom, the combination of a lead guide tube for conducting a lead stick from the magazine to said outlet, a lead-engaging member movable into and out of position to engage a lead stick in said tube, means for moving the lead-engaging member in both directions longitudinally of said tube, and a throw-off device for cooperation with said lead-engaging member to move it out of position to engage a lead stick in said tube incident to completion of its downward movement, said throw-off element being movable longitudinally of the tube with the lead-engaging member and being also movable longitudinally relative to the lead-engaging member.

3. In a mechanical pencil having a lead stick magazine and a channel for guiding a lead stick therefrom to the writing point, the combination of a lead-engaging member movable into and out of the path of a lead stick in said channel, means for moving said lead-engaging member in both directions longitudinally of said channel, and a throw-off element adapted for latching

engagement with the lead-engaging member to hold the latter out of the path of a lead stick in the channel, said throw-off element being movable longitudinally of the channel with the lead-engaging member when in latching cooperation therewith.

4. In a mechanical pencil having a lead stick magazine and a channel for conducting lead sticks therefrom to the writing point, the combination of a lead-engaging member movable into and out of said channel in directions transversely thereof, a throw-off element movable longitudinally relative to said channel, and means for moving said lead-engaging member longitudinally relative to said channel and into and out of cooperation with said throw-off element.

5. In a mechanical pencil having a lead-gripping device adjacent its lower end, together with a magazine for lead sticks and a channel for conducting lead sticks therefrom to the lead-gripping device, the combination of a traveler reciprocable longitudinally of said channel between the lead-gripping device and the magazine, a lead-engaging member carried by the traveler for abutting engagement with the upper end of a lead stick in said channel, said lead-engaging member being movable to a cast-off position clear of the path of movement of a lead stick in the channel, means for moving the traveler longitudinally of the channel, and means for cooperation with the lead-engaging member to hold it in cast-off position during its movement toward the magazine.

6. In a mechanical pencil having a magazine for lead sticks and a channel for conducting a lead stick from said magazine to the writing point, the combination of a lead-engaging member movable in both directions longitudinally of said channel, actuating means for so moving the lead-engaging member and effective to hold it at any point of adjustment in its path of longitudinal movement, said lead-engaging member being movable into and out of lead-engaging position relative to said channel, and throw-off means operably effective on said lead-engaging member at completion of its movement toward the writing point, said throw-off means adapted for cooperation with the lead-engaging member to hold it out of lead-engaging position during its movement toward the magazine.

7. In a mechanical pencil having a lead stick magazine spaced upwardly from the writing point and a longitudinal passage for conducting a lead stick from the magazine toward the writing point, the combination of a traveler movable in both directions longitudinally of the pencil, a lead-engaging member carried by said traveler and movable thereon to and from a position to engage a lead stick in said passage, resilient means urging the lead-engaging member to said lead-engaging position, actuator means operable to move the traveler longitudinally of the pencil, and a throw-off element cooperative with the actuator means to move the lead-engaging member out of lead-engaging position, said throw-off element being movable with the traveler toward the magazine.

8. In a mechanical pencil having a lead stick magazine spaced above its writing point and a passage for conducting lead sticks from the magazine to the writing point, the combination of a lead-engaging member movable in both directions longitudinally of the pencil between an upper limit position and a lower limit position,

actuator means operable to effect longitudinal movement of the lead-engaging member and adapted to hold the lead-engaging member stationary at any position intermediate said limit positions, resilient means for pressing the lead-engaging member to lead-engaging position in said passage, and a throw-off element cooperative with said actuator means to move the lead-engaging member out of lead-engaging position, said throw-off element being movable with the lead-engaging member toward its upper limit position and adapted to hold the lead-engaging member out of lead-engaging position during such movement.

9. In a mechanical pencil, in combination, a barrel, a lead guide tube extending longitudinally therein, a traveler slidable longitudinally on the lead guide tube, a lead-engaging member carried by the traveler and adapted for propelling engagement with a lead stick in the lead guide tube, a throw-off element slidable longitudinally on the lead guide tube, a stop for limiting downward movement of the throw-off element, said throw-off element being adapted to hold the lead-engaging member out of lead-engaging position, actuator means operable to move the traveler in both directions longitudinally of the lead guide tube, and means for holding the throw-off element for movement with the traveler.

10. In a mechanical pencil having a longitudinal passage for conducting a lead stick to the writing point, the combination of a lead-engaging member operable to propel a lead stick in said passage, actuator means operable to move the lead-engaging member longitudinally of the pencil, and lead-retracting means operable automatically to retract a lead stick in said passage, the lead-engaging members being movable relative to the lead-retracting means in the lead-propelling direction.

11. A mechanical pencil as specified in claim 10 and wherein the actuator means is adapted to hold the lead-engaging member against longitudinal movement at any point in its path of travel.

12. In a mechanical pencil having a longitudinal channel for conducting a lead stick toward the writing point, the combination of lead-propelling means operable to propel a lead stick in said channel, and lead-retracting means operable to impart retractive movement to a lead stick at the writing point, the lead-propelling means being operable independently of the lead-retracting means to propel the lead stick toward the writing point.

13. In a mechanical pencil, in combination, a lead guide tube extending longitudinally of the pencil, longitudinally movable lead-gripping means adapted to clutch a lead stick frictionally, lead-propelling mechanism operable to advance a lead stick in the lead guide tube and into engagement with said lead-gripping means, said lead-gripping means being movable toward the writing point by pressure from the lead-propelling mechanism, and yielding pressure means for moving said lead-gripping means away from the writing point to impart retractive movement to a lead stick gripped by it.

14. In a mechanical pencil, in combination, a lead guide tube extending longitudinally of the pencil and having a longitudinally extending lateral slot, means at the lower end of the lead guide tube for gripping a lead stick in writing position, a traveler movable longitudinally of the

- lead guide tube, actuator means for moving the traveler longitudinally, and a rigid lead-engaging member pivotally mounted on the traveler and having an inflexible arm portion adapted to extend through said slot and into the bore of the lead guide tube in position to abut the end of a lead stick therein, whereby the lead-engaging member may transmit longitudinal movement to the lead stick in one direction but not in the other. 5 80
- 10 15. In a mechanical pencil, the combination as specified in claim 14 and including yielding pressure means for forcing said arm of the lead-engaging member into the bore of the lead guide tube, and throw-off means movable longitudinally relative to the traveler and lead guide tube and adapted to hold said arm of the lead-engaging member clear of the bore of the latter. 15 85
- 15 16. In a mechanical pencil, the combination as specified in claim 14 and including a magazine arranged to dispense lead sticks successively into the lead guide tube and means for holding said arm of the lead-engaging member clear of the bore of said tube during upward movement of the traveler. 20 90
- 20 17. In a mechanical pencil, a magazine for holding a plurality of lead sticks and having an outlet opening of size such as to permit passage of lead sticks singly from the magazine, and a gauge member at the charging end of the magazine, said gauge member having a gauge opening affording the only entrance through which lead sticks may be introduced into said magazine, the width of the gauge opening being such as to permit passage of a single lead stick having a requisite small diameter, but the length of the gauge opening being such as to permit the passage of a plurality of such lead sticks simultaneously. 25 95
- 25 18. In a mechanical pencil, in combination, a hollow barrel, a lead guide tube arranged axially and non-rotatably therein, a tip abutting the lower end of the barrel and detachably connected to the lower end of the lead guide tube, thereby retaining the latter against withdrawal upwardly from the barrel, an actuator sleeve encompassing the upper portion of the lead guide tube and rotatable relative to the same and the barrel, an abutment in the barrel preventing downward movement of the actuator sleeve therein, the actuator sleeve being connected at its lower end to the lead guide tube to prevent upward movement of the former relative to the latter, a traveler slidably longitudinally on the lead guide tube and held against rotation thereon, said traveler having operative connection with said actuator sleeve whereby it is moved longitudinally upon rotation of the latter, a lead-engaging member carried by the traveler for cooperation with a lead stick in the lead guide tube, and means cooperating with the actuator sleeve and the upper end of the lead guide tube to maintain them in concentric relationship. 30 100
- 30 19. In a mechanical pencil, in combination, a lead guide tube having a longitudinal lateral slot communicating with its bore, a traveler movable longitudinally of the tube, actuator means for moving the traveler longitudinally of the tube in forward and rearward directions, a lead-engaging member movable on the traveler and spring pressed to its normal position wherein it extends into the tube bore through the longitudinal slot thereof in position to engage a lead stick in the tube during forward movement of the traveler, and means for holding the lead-engaging member in cast-off position clear of the tube bore throughout rearward movement of the traveler from its forward limit position. 35 105
- 35 40 18. In a mechanical pencil, in combination, a 110
